UNITED STATES PATENT OFFICE.

ANDREW HUETTER, OF DETROIT, MICHIGAN, ASSIGNOR OF FORTY-NINE ONE-HUNDREDTHREE TO KURT ROEHL, OF DAYTON, OHIO, AND TWENTY-FIVE ONE-HUNDREDTHREE TO ELFRIEDE BETTY HUETTER, OF DETROIT, MICHIGAN.

TUBE-SPlicing DEVICE.

Application filed July 21, 1924. Serial No. 727,387.

To all whom it may concern:

Be it known that I, ANDREW HUETTER, a citizen of the United States, residing at Detroit, in the county of Wayne and State 5 of Michigan, have invented certain new and useful Improvements in Tube-Splicing Devices, of which the following is a specification.

This invention relates to a tube splicing 10 press, particularly adapted for splicing inner tubes for pneumatic tires into endless or annular form.

In the present improvement there is contemplated an exterior form or matrix, and 15 an interior expandible mandrel of flexible, but inextensible material, preferably sheet metal, expanded by fluid pressure to subject the interposed overlapping ends of the tube to internal pressure. Such expansion 20 of the mandrel or interior form may be effected by compressed air hydraulic pressure or other fluid actuating means, but is preferably achieved by use of superheated steam, thereby simultaneously affording the necessary vulcanizing heat as well as the pressure. 25

The object of the invention is to simplify the structure as well as the means and mode of operation of tube splicing devices where- 30 by they will not only be cheapened in construction, but will be more efficient in use, uniform in operation, easily controlled and unlikely to get out of repair.

A further object of the invention is to 35 provide for such tube splicing presses, an expandible mandrel or core, which will readily withstand high degrees of temperature without deterioration, and will be quickly responsive to variations of internal pressure, 40 enabling the pressure to which the splice is subjected to be quite accurately gaged and varied at will of the operator in wide range of variation.

A further object of the invention is to 45 provide a press or mold for tube splicing wherein the splice will be subjected to either internal or external heat.

A further object of the invention is to 50 provide a splicing press which will enable a complete splice to be effected with minimum overlap of the end, thereby conserving and economizing material.

With the above primary and other in-

cidental objects in view as will more fully appear in the specification, the invention 55 consists of the features of construction, the parts and combinations thereof, and the mode of operation or their equivalents as hereinafter described and set forth in the 60 claims.

Referring to the drawings, Fig. 1 is a side elevation of the press, mounted for foot operation. Fig. 2 is a rear elevation of the press and Fig. 3 a vertical sectional view on line 3—3 of Fig. 1. Fig. 4 is a side elevation of the press or matrix mounted for hand operation. Fig. 5 is a top plan view and Fig. 6 bottom plan view of the expandible mandrel or core. Fig. 7 is an end elevation viewed from the left of Figs. 5 and 6, while Fig. 8 is an elevation from the right of such figures, the handle portion being omitted. Fig. 9 is a longitudinal sectional view and Fig. 10 a transverse sectional view of a modification of the expandible mandrel. Fig. 11 is a top plan view of the closure slide for the mandrel of which Fig. 12 is an end elevation from the left in Fig. 10, and Fig. 13 is an end elevation from the right of Fig. 10. 75

Like parts are indicated by similar characters of reference thruout the several views.

It has been estimated that at the present time, approximately ninety to ninety-five per cent of inner tubes for pneumatic tires are 80 spliced by the well known cold cure or acid method. This is the method most widely and generally employed. Such extensive use of the cold cure or acid method is primarily due to the fact that the hot cure or 85 vulcanization processes as heretofore attempted are not economical in labor costs, altho more reliable in effect. Not only is the present invention intended to overcome the objections generally recognized to the cold 90 cure or acid method of tube splicing, but it also enables a material saving in stock by effecting successful and complete splicing with approximately one half to one inch of 95 overlap of the tube ends, whereas the cold cure process ordinarily necessitates an overlap of the tube ends of several inches in extent. The press herein described is further designed to increase the speed of operation over that of the cold or acid process, 100 materially reducing losses due to lack of 105

contact or leaky joints, and by elimination of acid fumes to afford safe working conditions.

The matrix or female member comprises 5 two hollow semi-annular sections 1 and 2, hinged one to the other at 3. The interior chamber of each of these semi-annular members 1 and 2 is provided with an inlet 4, and an outlet 5 for the live steam or other heating medium, in the event that both interior and exterior heat is to be applied. The outlet ports 5 are preferably, tho not necessarily, interconnected one to the other by suitable flexible hose connections, in which case 10 the steam or other heating medium entering the port 4 of one member, will pass thence thru the other member.

The connections to the ports 4 leading to the interior chambers of the semi-annular members 1 and 2 are also connected by means 20 of flexible hose, thus enabling the matrix or female member to be opened by oscillation of the sections 1 and 2 about their hinge connection 3. For convenient mounting, 25 these members 1 and 2 are provided with oppositely disposed lugs 6. The lug 6 of the member 1 is pivotally connected to the upper arm of a C-shaped supporting frame 7, for oscillating movement in relation therewith. The corresponding lug 6 upon the opposing member 2 is connected to one end 30 of a lever 8, which in turn is pivoted at 9 to the lower arm of the C-shaped member 7. By oscillating the lever 8, the female member or matrix may be thrust forwardly and 35 at the same time opened about its hinged connection 3 to receive the tube and mandrel. Such operated or open position of the matrix is shown by dot and dash lines in Fig. 1. 40 Any suitable means may be employed for oscillating the lever 8. The preferred construction is by means of a treadle or foot operated lever 10, connected by a link 11 with the lower end of the lever 8. The treadle or foot lever 10 is shown in the drawing 45 provided with a pedal operated detent 12, locking the treadle 10 in its depressed position and holding the matrix closed. A spring 13 attached to the operating lever 8 50 thru the link 11 tends to retract the operating lever 8 and open the matrix by thrusting it forwardly upon release of the detent 12.

In lieu of such foot operated mechanism, 55 a hand lever 14 pivoted to the supporting frame 7 may be connected with the operating lever 8, as by a link 15, thereby effecting the same movement of the matrix to and from its closed position.

60 The interior surface of the matrix sections 1 and 2 are preferably tho not necessarily lined with arcuate sections of rubber, 16, fabric, composition or other suitable lining material. If rubber is employed, such lining 65 will be changed from time to time as the

rubber deteriorates or hardens under the influence of continuous or successive heating. The preferable lining material is one possessing the characteristics of rubber, yet unsusceptible to deteriorating influence of heat. 70

The expansible mandrel as shown in Figs. 5 and 6 comprises a longitudinally slotted tubular body of sheet metal having double walls. The interior and exterior walls of the tubular body are separated one from the other to afford an intermediate chamber for fluid under pressure or for heating medium. 75

As shown in Figs. 5 and 6 the mandrel or core 18 is substantially cylindrical in form thruout the greater portion of its length, 80 being slightly tapered or conical at its extremity to facilitate its engagement within the overlapped portion of the tube. The mandrel 18 is provided with a longitudinal tapered slot 19. In effecting a splice, one 85 end of the tube to be spliced is extended thru the interior of the mandrel and then turned backward over its extremity, where it is brought into contact with the opposite end of the tube to be joined. Upon completion of the splice, the annular or endless tube extends thru the interior of the hollow mandrel. The longitudinal slot 19 is for the purpose of enabling the tube to be removed from the mandrel after its ends have 90 been joined. A removable closure slide 20 is provided for such tapered slot 19. Such closure slide has been illustrated in Figs. 11, 12 and 13. The slide 20 is reduced at its opposite margins to feather edges, so that its 95 exterior surface will merge uniformly and smoothly into the exterior surface of the mandrel when such slide is engaged within the slot 19. The underside of the slide 20 is provided with lateral tapered grooves 21 100 in which the margins of the mandrel slot 19 engage. As illustrated by dotted lines in Fig. 11 and as shown in the end view Fig. 12, such lateral grooves or recesses are 105 comparatively deep at one end of the closure 110 slide 20, such grooves becoming more shallow as they approach the opposite end, finally terminating in shoulders or rabbets 22, as shown in Fig. 13. This closure slide 20 is 115 longitudinally adjustable into and out of the access slot 19 of the mandrel and when in position affords a continuous uniformly smooth exterior peripheral surface for the mandrel. To facilitate the disengagement 120 of the spliced tube after completion of the splicing operation the closure slide 20 is preferably, tho not necessarily provided with a longitudinal passage or duct 24 having at one end an inlet nipple 25, and terminating 125 at its opposite end in discharge orifices 26 thru which air under pressure may be introduced for loosening and separating the spliced tube from the mandrel in the event that there is any tendency to stick or adhere. 130

arily mounted, while the upper section 1^a, is hinged thereto at 3 in much the same manner as before described. A spring 36 connected to a rearwardly extending arm 37 upon the upper matrix section 1^a tends to oscillate such section upwardly and rearwardly, ready to receive the mandrel, and assembled tube. A hand lever 35 pivoted at 38 to the forward end of the matrix section 1^a is provided with a locking shoulder 39 engaging a corresponding shoulder 40 upon the lower matrix section to interlock such parts in engagement one with the other. This hand lever is actuated into locking engagement by the spring 41. The matrix sections 1^a and 2^a are provided with inlet and outlet ports leading to the hollow interiors for the admission of steam or other heating medium in the same manner as shown in Fig. 1.

From the above description it will be apparent that there is thus provided a device of the character described possessing the particular features of advantage before enumerated as desirable, but which obviously is susceptible of modification in its form, proportions, detail construction and arrangement of parts without departing from the principle involved or sacrificing any of its advantages.

While in order to comply with the statute the invention has been described in language more or less specific as to structural features, it is to be understood that the invention is not limited to the specific details shown, but that the means and construction herein disclosed comprises the preferred form of several modes of putting the invention into effect and the invention is, therefore, claimed in any of its forms or modifications within the legitimate and valid scope of the appended claims.

Having thus described my invention, I claim:

- 45 1. In a splicing press for tire tubes and the like, a pair of semi-annular matrix jaws interpivoted to each other, a support to which one of said jaws is further pivotally attached, and a lever pivotally attached to the other jaw by the movement of which the semi-annular jaws are oscillated in relation with the support and in relation with each other to open and close the jaws and a mandrel insertable within the jaws.
- 55 2. In a splicing press for tire tubes and the like, a toggle like structure including a mounting, a pair of interpivoted semiannular matrix jaws mounted upon the support for toggle like adjustment into distended and closed relation and operating means connected to one of the jaws for effecting their opening and closing movement, and a mandrel insertable between the jaws when distended.

3. In a splicing press for tire tubes and 65 the like, a pair of semiannular matrix jaws pivoted to each other, non-inflatable cushion lining pads for said jaws and an expansible mandrel insertable within the jaws.

4. In a splicing press for tire tubes and 70 the like, a pair of hollow semi-annular matrix jaws interpivoted one to the other, the hollow interiors affording inflexible steam chambers, steam inlet and outlet passages communicating with the hollow interiors of 75 the jaws, a hollow expansible mandrel of flexible but inextensible material insertable within said jaws, and inlet and outlet passages for fluid under pressure communicating with the interior of the hollow mandrel. 80

5. In a splicing press for tire tubes and the like, a pair of hollow semi-annular matrix jaws, interpivoted one to the other, the hollow interiors affording inflexible steam chambers, steam inlet and outlet passages 85 communicating with the hollow interiors of the jaws, yielding cushion pads positioned within said jaws, and a mandrel insertable within the jaws.

6. In a splicing press for tire tubes and 90 the like, a pair of hollow semi-annular matrix jaws interpivoted one to the other, the hollow interiors affording inflexible steam chambers, steam inlet and outlet passages communicating with the hollow interiors of 95 the jaws, and relatively movable pivotal connections for the jaws independent of their pivotal connections to each other by the adjustment of which the jaws are distended and contracted. 100

7. In a splicing press for tire tubes and the like, a pair of semi-annular matrix jaws interpivoted one to the other, supporting means to which the jaws are each separately pivoted independent of their pivotal connection one to the other, spring means for relatively oscillating the jaws into open relation, and an operating lever operating in opposition to the spring for closing the jaws, and an expansible mandrel insertable within 110 the jaws when open. 105

8. In a splicing press for tire tubes and the like, a pair of semiannular matrix jaws, interpivoted one to the other, the pivotal connection of the jaws being movable to 115 and fro simultaneously with the interpivotal movement of the jaws, means for oscillating both jaws simultaneously to effect a forward thrust and retrograde movement of the jaws in the opening and closing movements, and a mandrel engageable within said jaws. 120

9. In a splicing press for tire tubes and the like, a pair of hollow semi-annular matrix jaws movable relatively one to the other, steam inlet and outlet passages communicating with the hollow interiors of said jaws, and an expansible mandrel having 125

The underside of the mandrel or that side opposite the access slot 19 is provided with hollow bosses 27, communicating with the interior chamber 28 of the hollow walls of the mandrel. Inlet and outlet conduits 29 and 30 communicate with such hollow bosses 27, thru which fluid under pressure or heating medium or both are admitted to the chamber 28 and exhausted therefrom. The mandrel is provided with longitudinally extending furcations or arms 31 at one extremity, to which is attached a handle 32 formed in two sections interpivoted at 33 to compensate for the expansive movement of the mandrel. The handle 32 is preferably formed with an open bight 34, in which the surplus portion of the tube being spliced may be engaged to support it conveniently while the ends to be spliced are engaged over the mandrel.

In preparing for a splice, one end of the tube is inserted thru the tubular hollow walled mandrel, either by passing it from one end to the other thru the interior of the mandrel, or by collapsing the tube and sliding it laterally thru the longitudinal access slot 19. The closure slide 20 is then placed in position with the margins of the access slot 19 engaging in the lateral grooves or recesses of the closure slide and the slide is forced longitudinally sufficient to afford a slight breaking action, sufficient to retain it in position. The end of the tube passed thru the mandrel is then reversed inside out over one end of the mandrel. This reverse portion of the tube is then again reversed upon itself, and the opposite end of the rubber tube is passed around the doubly reversed tube end surrounding the mandrel. This will bring the interior surface of one end of the tube into contact with the exterior surface of the opposite end of the tube.

The matrix comprising the hinged annular sections 1 and 2 being in its forward and open position, the mandrel with the overlapped ends of the tube positioned thereon is placed within the open matrix and the lever 8 is operated to close the matrix over the overlapped ends of the tube and mandrel. Various operators have different theories and ideas as to the best method of vulcanization. The present press is so constructed as to meet various conditions of operation and to enable the operator to apply heat either externally or internally or both externally and internally as he may elect. If the operator prefers to employ heat externally only, superheated steam is admitted to the interior chambers of the members 1 and 2 of the matrix, and at the same time compressed air, water under pressure or other fluid pressure medium is admitted to the chamber 28 of the hollow mandrel, thereby expanding the mandrel within the heated matrix and subjecting the inner-

posed overlapping portions of the tire to internal pressure. If it is desired to equalize the heat internally and externally, superheated steam may be admitted to the chamber 28 of the hollow mandrel, affording both the expansive internal pressure and the internal heating medium. It will also be obvious that in the event that internal heat only is required, steam need not be admitted to the sections 1 and 2 of the matrix, but the vulcanizing heat may be supplied wholly from the hollow expansive mandrel internally of the tire. The fluid pressure within the mandrel whether it is superheated steam or merely compressed air or water pressure, serves to flex the yielding walls of the mandrel expanding the mandrel by separating the margins of the access slot 19 beneath the overlapping closure slide 20 and subjecting the tube to internal pressure.

If a cement splice or acid cure method is employed, heat is not required in either the mandrel nor the matrix. The press may be employed for such cold cure process by utilizing compressed air or hydraulic pressure or other fluid pressure medium in lieu of superheated steam. Various methods of assembling the tube ends preparatory to splicing are now in common use. The method heretofore described has been referred to for illustrative purposes only and not with any intent to limit the present invention or the use of the press to such particular splicing method. It is to be understood that various other forms of splicing relation of the tube ends may be employed. The mandrel which as before described is preferably of a sheet metal cylindrical formation having therein a reentrant tubular loop or plait of comparatively large dimension, is preferably made from sheet copper or copper alloy, which have been found quite suitable for this purpose. However, other materials having heat resistant properties and a reasonable degree of elasticity or flexibility even tho non-metallic may be employed with equally advantageous result. The inner and outer walls of the mandrel are united at its extremities and also along the margin of the access slot 19, forming within the mandrel the substantially crescent shaped steam chamber 28.

In Figs. 9 and 10 there have been shown a modification of the mandrel, wherein the interior wall of the mandrel and steam chamber 28 is longitudinally corrugated as at 42. Such corrugations readily compensate for the expansion or outward flexing of the outer walls of the mandrel, and render the mandrel somewhat more responsive to the influence of the fluid pressure within the chamber 28.

In Fig. 4 there has been shown a modification of the matrix or exterior press members, wherein the lower section 2^a is station-

therein an expansion chamber and means for admitting fluid under pressure to said mandrel.

10. In a splicing press for tire tubes and the like, a pair of hollow semi-annular matrix jaws movable relatively one to the other, steam inlet and outlet passages communicating with the hollow interiors of said jaws, an expansible metallic mandrel having

10 a steam chamber therein and steam inlet and outlet passages leading to the expansible mandrel by the admission of which the mandrel is simultaneously expanded and heated.

15 11. In a splicing press for tire tubes and the like, a pair of hollow semi-annular matrix jaws, movable relatively one to the other, an expansible metallic mandrel having therein a steam chamber and steam inlet

20 and outlet passages communicating with the steam chamber by the admission of which the mandrel is simultaneously heated and expanded.

12. In a splicing press for tire tubes and the like, a pair of hollow semi-annular matrix jaws movable relatively one to the other, and a mandrel co-acting therewith comprising a longitudinally slotted tubular member having double spaced walls of flexible sheet

30 metal forming intermediate such walls a chamber for fluid under pressure, a removable closure for the longitudinal slot of said mandrel, the exterior face of which merges comparatively smoothly into the surface of

35 the mandrel, and means for admitting fluid under pressure to the chamber within the walls of the mandrel while within the matrix jaws for expanding the mandrel there-

40 within.

40 13. In a splicing press for tire tubes and the like, a pair of hollow semi-annular matrix jaws movable relative one to the other, an expansible metallic mandrel having double spaced walls forming an intermediate

45 chamber for fluid under pressure, said mandrel being of cylindrical form throughout the greater portion of its length, the terminal portion thereof being exteriorly tapered, and means for admitting fluid under pres-

50 sure to expand the mandrel within the matrix jaws.

14. In a splicing press for tire tubes and the like, a pair of hollow semi-annular matrix jaws movable relatively one to the other,

55 and a cylindrical longitudinally slotted expansible tubular mandrel having double spaced walls affording an intermediate chamber for fluid under pressure, and a removable compensating closure for said longitudinal slot operative through various degrees of expansion of the expansible mandrel.

15. In a splicing press for tire tubes and the like, a pair of hollow semi-annular ma-

trix jaws, movable relatively one to the other, an expansible longitudinally slotted tubular mandrel, and a handle carried at one end of the mandrel, said handle being flexible to compensate for expansion and contraction of the mandrel.

16. In a splicing press for tire tubes and the like, a pair of hollow semi-annular matrix jaws movable relatively one to the other, an expansible mandrel co-operating with the jaws, and a flexibly connected handle for

75 said mandrel, the flexibility of which compensates for the expansion and contraction of the mandrel, and means for expanding the mandrel within the matrix jaws.

17. In a splicing press for tire tubes and the like, a pair of hollow semi-annular matrix jaws movable relatively one to the other, an expansible mandrel coacting with the jaws, and a two part handle for the mandrel, the parts of which are pivotally connected to compensate for the expansion and contraction of the mandrel.

18. In a splicing press for tire tubes and the like, a pair of hollow semi-annular matrix jaws movable relatively one to the other, an expansible mandrel coacting with the jaws, and a handle, the handle having therein a bight formed with a restricted mouth to receive the surplus portion of the tire tube being operated upon.

19. A tube splicing device including an expansible metallic mandrel, and means for exerting pressure against the splice by the introduction of fluid under pressure into the mandrel.

20. A tube splicing device including a hollow expansible metallic mandrel and means heating the splice by the introduction of heated fluid under pressure into the hollow mandrel.

21. A tube splicing device, including an expansible mandrel, and means for simultaneously heating the splice and applying pressure thereto by the introduction of fluid under pressure into the mandrel.

22. In a splicing press for endless pneumatic tubes and the like, a pair of semi-annular matrix jaws, each jaw pivoted to a frame and also to each other.

23. In a splicing press for endless pneumatic tubes and the like, an annular matrix comprising a number of independent arcuate sections, a mounting to which each section is pivoted, each section being also pivoted to the adjoining section.

24. In a splicing press for endless pneumatic tubes and the like, a matrix comprising a pair of semi-annular jaws, interpivoted one to another, and each jaw being further pivoted, one to a stationary mounting frame, the other to a fulcrumed lever, by the operation of which the jaws are spread outwardly and divergently in relation to each other.

25. In a splicing press for endless pneumatic tubes and the like, an annular matrix comprising a number of arcuate sections, interpivoted one to another and a frame in which the sections are each further pivoted.

26. A tube splicing device or the like, a matrix comprising a pair of semi-annular jaws and an expansible mandrel within said jaws, the expansion of which exerts pressure against the ends of the tube to be spliced, and means for introducing fluid under pressure between the mandrel and the

spliced tube to free the tube from the mandrel.

27. A tube splicing device or the like, a matrix and an expansible mandrel between which the ends of the tube are to be spliced, and means for freeing the tube in event it sticks to the mandrel by means of compressed fluid introduced between the mandrel and tube.

In testimony whereof, I have hereunto set my hand this 7th day of July A. D. 1924.

ANDREW HUETTER.
